UNITED STATES PATENT OFFICE.

GEORGE I. HIPPLE, OF CHICAGO, ILLINOIS.

OPERATING MECHANISM FOR JACKS.

Application filed December 22, 1920. Serial No. 482,934.

To all whom it may concern:

Be it known that I, GEORGE I. HIPPLE, a citizen of the United States, residing at Chicago, in the county of Cook and State of Illinois, have invented a new and useful Improvement in Operating Mechanisms for Jacks, of which the following is a specification.

My invention relates to an improved operating mechanism for jacks for lifting purposes, particularly relatively small jacks used in connection with motor vehicles and it comprises a handle for operating the jack which may be folded when not in use and secured together in use to constitute in effect a rigid member for operating the jack by an oscillating motion. My improved operating mechanism is adapted for use in connection with jacks actuated by moving pawls and I provide a reversing mechanism on my handle by which either desired pawl may be made operative and at the same time moving the other pawl to inoperative position, which reversing mechanism extends along the operating handle so that it may readily be engaged at a distance from the column of the jack thus making the reversing mechanism more accessible when the jack is under the axle of a vehicle than would be the case if it were necessary to reach under the vehicle to operate the reversing mechanism.

My invention will best be understood by reference to the accompanying drawings showing a preferred embodiment thereof in which—

Fig. 1 shows my operating mechanism in side elevation in place on a jack,

Fig. 2 is a plan view of the pawl and ratchet operating devices and the reversing mechanism associated therewith shown in Fig. 1,

Fig. 3 shows in rear elevation the gearing employed in connection with the jack.

Fig. 4 shows in a view similar to Fig. 1 but from the opposite direction, my improved handle construction with a modified form of reversing mechanism for controlling the position of the operating pawls,

Fig. 5 shows in plan view the central portion of the handle shown in Fig. 4 and

Fig. 6 shows in plan view the portions of the handle construction shown in Figs. 5 in folded relation.

Similar numerals refer to similar parts throughout the several views.

As shown in Figs. 1, 2 and 3, the construction consists of a column 10, which is hollow to receive a screw 11 carrying at its upper end a saddle 12. The screw 11 has 60 threaded thereon a bevel gear 13 meshing with a second bevel gear 14 mounted to rotate on a stud 15 rigidly secured in the upper end of the column 10 and extending laterally therefrom. The gear 14 is rigidly secured to 65 the ratchet wheel 16 engaged by one or the other of the pawls 17 and 18 depending upon the direction of rotation to be imparted to the gear 13. An operating handle consisting of two bars 19 and 20 is supported on the 70 stud 15 by means of an enlarged end 21 formed on the portion 20 which is bored to slip over the end of said stud on which it is held by any suitable means. The enlarged portion 21 is also extended upwardly and 75 pivotally carries the pawls 17 and 18 on a pin 22. The pawls 17 and 18 have extending laterally therefrom pins 23 and 24 respectively engaged by the cam surfaces 25 and 26 carried by the reversing bar 27 which is 80 mounted to slide on the member 20 of the handle. The bar 27 is held in place by suitable rivets 28 which pass through slots in said bar to permit the sliding motion referred to and said bar has formed on its 85 outer end an ear or lug 29 to be engaged by the operator.

The portions 19 and 20 of the handle are pivotally connected at 30 by a suitable rivet or bolt and the portion 19 carries a thumb 90 screw 31 which may be screwed into the portion 20 of the handle when in use or unscrewed from said portion 20 to permit the folding of the portion 19 on the bolt 30 against the portion 20 of the handle.

As more clearly shown in Fig. 5 the thumb screw 31 is provided with a flange 32 which prevents its ready removal from the portion 19, suitable clearances being provided in the portions 19 and 20 of the handle to permit 100 the flange to move from one of its extreme positions to the other.

As a result of the construction described it will appear that when not in use, the handle, which for convenience and easy operation, should be substantially twice as long as the height of the column of the jack, may be folded into substantially the length of the column and lie close to the column and parallel therewith and thus occupies a 110 minimum of space which is desirable in connection with storing the jack; also that in

its folded condition there are no loose parts. It will be further observed that either of the operating pawls may be moved away from the ratchet wheel by the movement of the reversing bar when the jack is in use without requiring the operator to reach to the jack itself, thus reducing the liability of soiling the clothes and making the adjustment of the pawls a much easier operation than where it is necessary to reach to the jack itself. Furthermore the handle in its extended position with the clamping screw in place forms a very convenient means for moving the jack to its proper position and for removing the jack after it has been used without requiring the operation to reach under the vehicle to be raised by the jack.

In the modified construction shown in Fig. 4 the handle construction is the same as described above and the pawls 17 and 18 are similarly carried by the handle, the only difference being that the reversing bar 27^a is mounted on the opposite side of the portion 20 from that on which the reversing bar 27 is supported. The operation of the reversing bar is substantially the same as described above for the reversing bar 27, motion in one direction raising one of the pawls and permitting the other pawl to be operative while motion in the other direction reverses the relation of the pawls to the ratchet wheel.

While I have shown my invention in the particular embodiment above described, it will be understood that I do not limit myself to this exact construction as I may employ equivalents known to the art at the time of the filing of this application without departing from the scope of the appended claims.

What I claim is:

1. In a lifting jack, the combination of a column, a bar movable in the column, gearing for moving the bar relatively to the column including two pawls for moving said bar in opposite directions, a handle pivotally connected to said column and carrying said pawls, and a member carried by said handle and movable relatively thereto for controlling the operative relation of said pawls at a point remote from said column.

2. In a lifting jack, the combination of a column, a bar movable in the column, gearing for moving the bar relatively to the column including two pawls for moving said bar in opposite directions, a handle pivotally connected to said column and carrying said pawls, and a member carried by said handle, and movable relatively thereto for controlling the operative relation of said pawls at a point remote from said column, said gearing comprising a first bevel gear threaded on said bar, a second bevel gear

meshing with said first gear, and a ratchet wheel secured to said second gear to be engaged by said pawls.

3. In a lifting jack, the combination of a column, a bar movable in the column, gearing for moving the bar relatively to the column including two pawls for moving said bar in opposite directions, a handle pivotally connected to said column and carrying said pawls, and a member carried by said handle for controlling the operative relation of said pawls at a point remote from said column, said gearing comprising a first bevel gear threaded on said bar, a second bevel gear meshing with said first gear, and a ratchet wheel secured to said second gear to be engaged by said pawls, and said member comprising a reciprocable bar having lugs for engaging said pawls to move either of them as desired to inoperative position and permit the other of them to operate.

4. In a lifting jack, the combination of a column, a bar movable in the column, gearing for moving the bar relatively to the column including two pawls for moving said bar in opposite directions, a handle pivotally connected to said column and carrying said pawls, and a member carried by said handle for controlling the operative relation of said pawls at a point remote from said column, said member comprising a reciprocable bar having lugs for engaging said pawls to move either of them as desired to inoperative position and permit the other of them to operate.

5. An operating mechanism of the class described comprising a handle having a bearing at one end, two pawls carried by said handle adjacent said bearing and movable to operative and inoperative positions, and a reversing member extending along said handle from said pawls for moving either pawl to inoperative position and permitting the other pawl to assume its operative position.

6. An operating mechanism of the class described comprising a handle having a bearing at one end, two pawls carried by said handle adjacent said bearing and movable to operative and inoperative positions, and a reversing member extending along said handle from said pawls for moving either pawl to inoperative position and permitting the other pawl to assume its operative position, said member comprising a bar mounted to slide on said handle and having a lug extending from its outer end to be engaged by the operator.

In witness whereof, I hereunto subscribe my name this 13th day of December, A. D. 1920.

GEORGE I. HIPPLE.
